ELECTRIC SWITCH AND LIGHT FIXTURE

Thomas J. Mudon, Chicago, Ill., assignor to Safe Delay Switch Corporation, Chicago, Ill., a corporation of Illinois

Application May 12, 1941, Serial No. 393,097

14 Claims. (Cl. 200—33)

The present invention relates to time delay control mechanisms and comprises an improvement upon the time delay control mechanism covered by my previous Patent No. 2,202,297 of May 28, 1940. In the patent there is disclosed a time delay control mechanism whereby the time lag is accomplished by moving a creeping element along a track.

It is the principal purpose of the present invention to provide an improved time delay control mechanism comprising a creeping element and a track together with means for varying the pressure between the creeping element and track in response to changes in temperature. I have discovered that the rate of creeping of the creeping element in this combination is peculiarly responsive to changes in temperature. When warmed up the rate of creeping speeds up and when cooled the rate of creeping is slower. This is particularly true where the creeping element is made of rubber, either of the natural or synthetic type. This characteristic of change in creeping speed due to relatively remote changes in temperature (which characteristic I term "nerve lag") results in a sufficient variation in the rate of creeping to prevent a serious problem in the accurate timing of the delay accomplished by the use of the creeping element and track.

Specifically I have found that by using, in the supporting means for the creeping element and track, a temperature responsive member such as a bimetallic strip I am able to compensate for the change in nerve lag of the creeping element. I thus can maintain a time lag setting constant over a sufficiently wide range of temperatures for all practical operations.

In its simplest form the new combination comprises a creeping element of rubber, either natural or synthetic, and a track element comprising a bimetallic bar. Pressure is applied through the mounting of the bimetallic bar which is at some distance from the point of engagement of the track and the creeping element. The bar is so mounted that as the surrounding atmosphere warms up and the temperature of the creeping element therefore increases the bar moves the part of the track engaged by the creeping element toward the creeping element thus to increase the pressure between the track and the element to offer greater resistance to the creeping action. When the surrounding atmosphere cools the temperature of the creeping element decreases but at the same time the bar moves the track away from the creeping element so as to decrease the pressure between them and make it

easier for the element to creep along the track.

My invention is not confined however to such a simple combination as the temperature compensating means may be of any other suitable form capable of causing separation of the creeping element and track as the temperature decreases or causing them to approach each other as the temperature increases. It is immaterial to the present invention in its broader aspects whether the track or the creeping element be stationary. It is only essential that they be pressed against each other and that a definite force be provided to move one with respect to the other.

15 In the several forms of the invention shown herein, the features of which comprise specific features of novelty, spring means is used to provide the definite force by which the movement of the creeping element along the track is caused. 20 Also, means are provided whereby the period of delay may be carried by the simple expedient of varying the pressure of the creeping element upon the track.

25 The preferred form of my invention is illustrated in and comprises a time delay control switch mechanism for connecting a source of current such as a battery to a small lamp in a unit which is adapted to serve as a source of illumination in closets and other small dark areas where illumination by the usual lamp has not been provided. It will be appreciated that a portable unit of this type, self-contained in its entirety, finds a multitude of applications in existing structures. It has the advantage that constant drain upon the power source is avoided because the time delay control mechanism automatically disconnects the power source from the lamp after a predetermined time and yet the unit remains ready at any time to furnish light in the dark area where it is situated.

30 Other and more specific objects and advantages of the invention will appear as the description proceeds, reference being had to the accompanying drawings wherein a preferred form of the invention and a number of mechanical modifications thereof are illustrated. It is to be understood however that the drawings and description are illustrative only and should not be taken as limiting the invention beyond the scope to which it is justly entitled in view of the prior art and in accordance with the appended claims.

Fig. 19 is a view similar to Fig. 18 illustrating the parts in changed position;

Fig. 20 is a view in side elevation of a further modification; and

Fig. 21 is a fragmentary sectional view taken on the line 21—21 of Fig. 20.

Referring now in detail to the drawings, the present invention is illustrated as a time delay control mechanism whereby a lamp 22 may be illuminated for a short time on a source of current comprising suitable dry cells 23, 24 and automatically turned off. The lamp and dry cells are mounted in a casing 25 which comprises a back plate 26 and a shell 27 having a front portion 28 that is translucent. Preferably the front portion 28 comprises a sheet of transparent or translucent plastic material such for example as the material sold under the trade name "Lucite." The shell 27 is preferably of metal and the back plate 26 is of insulating material; for example, a synthetic resin compound such as that sold under the trade name "Bakelite." A mounting clip 29 is fastened at the top of the casing 25 so that the entire device may be hung on a nail or other simple mounting means. Within the casing 25 I provide suitable holding spring brackets 30 and 31 upon which the dry cells 23 and 24 rest. I also provide side supports 32 and 33 and top clips 34 and 35 for engaging the dry cells. The several elements just described are fastened to the back plate 26 by screws. The top clips 34 and 35 are connected together by a cross bar 36 so that they may serve with the cross bar as a conductor for con-

necting the two dry cells in series. The spring bracket 31 forms part of a plate 37 that extends upwardly along the back plate 26 and then toward the center of the back plate where it is offset at 38 to provide a lamp mounting 39 for the lamp 22. A screw socket 40 is provided on the portion 39 to receive the screw threaded base of the lamp 22. The opposite terminal of the lamp at the center tip is engaged by a spring contact 41 which is mounted upon a frame 42 for the time delay control mechanism. The frame 42 is fastened to the back plate by suitable screws and the mounting of the spring contact 41 is such as to insulate it from the frame 42. The frame 42 is however directly connected to the supporting spring brackets 30 by a contact strip 43.

The time delay control mechanism is carried entirely by the frame 42. The spring contact 44 is electrically connected to the contact spring 41 and extends downwardly inside the frame 42 as shown in Figs. 1 to 3, inclusive, the free end of this spring contact being bent outwardly as shown in Fig. 1. The frame 42 supports a spring plate 45 which is riveted at 46 to the frame and which is bent into substantially L-shape. Two ears 47 and 48 are turned up on the plate 45 near its free end. These ears support a pivot pin 49 which serves as a pivot for two arms 50 and 51 that carry a creeping element 52 of rubber which is firmly fixed to a supporting bar 53. The ends 54 and 55 of the supporting bar 53 are rectangular in cross section and are slidably mounted in diagonal slots 56 and 57 in the arms 50 and 51. The end portions 54 and 55 are urged toward one end of their respective slots by springs 58 and 59 which are mounted on the arms 50 and 51. It will be noted from an examination of Fig. 6 that the creeping element 52 is directly molded onto a roughened portion 53a of the bar 53. This is to insure adhesion of the creeping element to the bar and to prevent any possibility of the creeping element becoming rotatable upon the bar.

The creeping element is urged from the dotted line position indicated in Fig. 2 toward the full line position by a spring 60 which is coiled around the pin 49. One end 61 of the spring presses against the plate 45 and the other end 62 extends lengthwise of the arm 51 and is secured thereto. The arm 50 serves as a contact element for engagement with the spring contact 44. When the creeping element is in the full line position shown in Fig. 2 the spring contact 44 does not engage the arm 50 and the circuit for the lamp 22 is open. However, when the creeping element is in the dotted line position shown in Fig. 2 the spring contact 44 is in engagement with the arm 50 and therefore the circuit for the lamp 22 is closed.

A track element 63 is fixed upon a flange 64 of the frame 42 so as to extend downwardly into the path of movement of the creeping element 52. The track element 63 is slotted and is held in place by a screw that threads into the flange 64. It is thus possible to initially adjust the position of the track element 63. The track element 63 has its creeping element engaging portion 65 offset as shown best in Figs. 2, 4 and 5 and has an extension 66 extending at an angle outwardly from the engaging portion 65 for a purpose which will presently appear. The track element 63 always presses against the creeping element during the time delay operation, the pressure being controlled by an adjust-

ing screw 67 which is threaded in a boss 68 on the frame 42 and which engages under a curved portion 69 at the free end of the plate 45. It will be evident from an inspection of Fig. 2 that by moving the screw 67 inward or outward the creeping element will be pressed toward or away from the track element. If more pressure is applied between the two elements the rate at which the creeping element will traverse the track element is slower. Also, if the temperature of the creeping element drops the rate at which the element creeps with respect to the track becomes slower. In order to compensate for the changes in creeping rate due to temperature changes I so mount the track element as to cause it to recede from the creeping element upon a drop in temperature and to approach the creeping element upon a rise in temperature. This is accomplished by making the track element 63 of a bimetallic, thermostatic material wherein one strip of metal 63a has a different rate of expansion than the other strip of metal 63b in response to temperature changes. The strip 63b has the greater response to temperature changes so that upon cooling it contracts faster than the strip 63a, thus tending to curve the combined strip in a counterclockwise direction about its point of support as illustrated in Figs. 2 and 4.

In order to move the creeping element into operative position I provide a pull chain 70 which is fastened to the arm 50 supporting the creeping element. This pull chain passes through an opening 71 in the bottom of the shell 27. The opening 71 has a reduced portion at 72 into which the pull chain may be hooked when it is desired to maintain the lamp 22 lighted for a period of time longer than the time delay provided by the creeping element and track. If it is desired at any time to break the circuit of the lamp 22 without waiting for the creeping element to complete its travel across the track the operator can press a plunger 73 upwardly against the angularly extending portion 66 of the track to thus move the track away from the creeping element enough to release the creeping element instantaneously. The plunger 73 is carried in the shell 27 and is prevented from dropping out by a pin 74.

The frame 42 is provided with means to limit the downward movement of the creeping element. This means comprises an offset extension 75 which extends into the way of the arm 51.

In the operation when it is desired to close the circuit for the lamp 22 the creeping element is moved down by a pull on the chain 70. As the creeping element passes downwardly over the track portion 65 it is permitted to back up because the rectangular end portions 54 and 55 of the bar 53 can slide along the slots in the arms 50 and 51 against the pressure of the springs 58 and 59. It therefore requires very little pressure to move the creeping element past the track portion. This avoids excessive wear on the creeping element and makes the mechanism easier to operate. However, when the movement of the creeping element is in an upward direction as illustrated in Fig. 5 the rectangular portions 54 and 55 have moved out under the influence of the springs 58 and 59 to the other ends of the slots 56 and 57 so that the full pressure contemplated in the setting of the screw 67 is now exerted between the creeping element and the track.

Referring now to Figs. 7 to 11, inclusive, in 75

these figures the time delay mechanism is mechanically of a slightly different construction although there is no change in the creeping element and its mounting or in the track element and its mounting.

To avoid confusion the same reference numerals are applied to the same parts wherever these parts have not been essentially changed. In this form of the invention the frame 42 is provided with two ears 76 and 77 in which a pin 78 is journaled to provide a pivotal support for the arms 50 and 51 that carry the creeping element 52. In this form of the invention there is a pin 79 passing between the two arms 50 and 51 adjacent to the creeping element 52. A coil spring 80 is wound about the pin 78, one end 81 of the spring bearing against the pin 79 and the other end 82 thereof being bent around a reduced end portion 83 upon an adjusting screw 84 that is threaded in the frame 42. By turning the screw 84 the tension of the spring 81 may be increased or decreased to thus govern the force tending to make the creeping element 52 traverse the track element 63. The operating mechanism in this form of the invention comprises a lever 85 which is pivoted on the end of the pin 78 outside of the arm 51. A spring 86 is coiled around the pin 78 outside of the lever 85 and normally tends to move the lever 85 into its inoperative position, that is, the position shown in Fig. 8. The pin 79 extends through the arm 51 and provides a post 87 which is adapted to cooperate with a spring latch 88 that is mounted on the frame 42. The spring latch 88 is offset at 89 intermediate its ends and has its free end portion 90 slightly diverging outwardly. The lever 85 is offset at 91 to extend inwardly across the arm 51 and is then bent at substantially right angles as shown at 92 in Fig. 7 so as to extend through a slot 93 in the frame 42. The free end of the extension 92 has a pull chain 94 thereon.

The operation of the device is as follows:

Assuming that it is desired to move the creeping element from the position shown in Fig. 8 to the position shown in Fig. 10, which would be the normal circuit closing position, the lever 85 is moved by means of the pull chain 94. Its offset portion 91 engages the arm 51 and moves the creeping element with it to the position shown in Fig. 10. The spring latch 88 engages over the post 87 and locks the creeping element in the position shown in Fig. 10.

The contact elements for the switch mechanism have been left off the modifications since they are no different than those employed in the main form of the invention. It will be evident however that when the parts are in the position shown in Fig. 10 contact would be established between the arm 50 and the spring contact 44. This contact will be maintained as long as the latch 88 is permitted to engage over the post 87. However when the operator desires to put the time delay mechanism to work by bringing the creeping element 52 into contact with the track 63 he again operates the lever 85 which in the meantime has returned to its original position under the force of the spring 86. This time upon operation the lever 85 engages under the spring latch 88 because the free end is turned out by the pull exerted on the spring latch by the post 87. The spring latch is thus lifted off of the post 87 as illustrated in Fig. 11 and the creeping element is permitted to come into contact with the track element. The time delay action then takes place the same as in the main form of the in-

vention. With this device it is therefore possible to close a circuit for as long a time as is desired and then by another operation of the switch lever to throw the time delay mechanism into operation so that the circuit will thereafter remain closed only for the predetermined time that it takes for the creeping element to pass across the track. This mechanism is particularly useful in such places as coal bins, fruit cellars and the like where at many times it is desirable to have a light on for a substantial period of time; yet it is desirable also to be able to get out of the dark space before the light goes out.

Referring now to the modification illustrated in Figs. 12 to 15, inclusive, in this modification all of the electrical connections have been left off for the sake of clearness.

The frame 42 and the mounting of the arms 50 and 51, together with the creeping element 52 and the track element 63, are identical with the modification just previously described. In this form of the invention however the setting of the time delay mechanism is accomplished by a sliding bar 95. The bar 95 is slidably mounted in the opposite sides of the frame 42. The bar is notched as indicated at 96 with a relatively deep notch having a long sloping surface 97. The bar is further notched at 98 with a small notch in the form of a broad V. A latch element 99 is fixed to the frame 42 at 100 and extends parallel with the direction of movement of the bar 95 past the arm 50 which carries the creeping element 52. In this form of the invention there is a post 101 projecting from the arm 50 and the latch 99 has an aperture 102 into which the post extends. The free end 103 of the latch 99 is offset toward the bar 95 and overlaps it as shown in Fig. 14. This free end is formed into a broad V-shape to match the notch 98. On the side opposite the notches 96 and 98 the bar 95 is cut out as illustrated at 104 (see Figs. 13 and 15).

The operation of this form of device is as follows:

Assuming that the operator desires to set the time delay switch mechanism to work he would normally find the parts in the position illustrated in Fig. 12. In this position the spring latch 99 would be resting in the notch 98 and the time delay creeping element would be free of the track. By pressing down upon the bar 95 to move the bar from the position shown in Fig. 12 to that shown in Fig. 14 the operator causes the notch 104 to move the arm 50 down to the position shown in Fig. 14. At the same time the downward movement of the bar 95 causes the end 103 of the spring latch 99 to move into the notch 96. This permits the post 101 to move into the aperture 102 and lock the arm 50 in the position shown in Fig. 14. This is the circuit closing position in accordance with the first form of the invention. Now when it is desired to set the time delay mechanism into operation the bar 95 is returned to its original position. This causes the spring latch 99 to be lifted so that the post 101 is released from the aperture 102 and the creeping element 52 is allowed to engage the track 63. The time delay action then takes place in the same fashion as in the main form of the invention.

Referring now to the form of device illustrated in Figs. 16 to 19, inclusive, in this form of device, as before, the frame 42, the creeping element 52 and the track 63 are constructed the same as in the modification illustrated in Figs. 7 to 11, inclusive. In this form of the invention however

the operating mechanism by which the creeping element is moved to operating position comprises a shaft 105 (see Fig. 17) having a knob 106 thereon, the shaft being journaled in two suitable ears 107 and 108 provided on the frame 42. This shaft has fixed thereto a cam arm 109 which lies just outside the ear 107 on the frame 42. This cam arm 109 has a free end portion 110 which extends inwardly beyond the arm 51 so that when the shaft 105 is turned from the position shown in Fig. 16 to the position shown in Fig. 19 the extension 110 engages with the arm 50 and moves the creeping element from the position shown in Fig. 16 to the position shown in Fig. 19. A spring 111 is wound about the shaft 105 and is under tension tending to turn the shaft to the position where the cam arm 109 is held out of contact with the arm 50. The friction of the portion 110 on the arm 50 is however sufficient to hold the shaft 105 against turning when the parts are in the position shown in Fig. 19.

In this form of the invention I have illustrated a simple contact mechanism that provides a novel combination with the time delay mechanism. This contact mechanism comprises two stationary spring contacts 112 and 113 which are mounted upon but insulated from the frame 42. The plate 114 of insulating material is pivoted upon the supporting pin 78 which also supports the arms 50 and 51. This plate carries a spring contact 115. The pin 79 has an extension 116 which extends outside the arm 51. The plate 114 has a large round aperture 117 into which the extension 116 extends. When the creeping element 52 is released from the track 63 the springs cause it to advance rapidly and the extension 116 therefore snaps against the wall of the aperture 117 so as to quickly break the contact between the movable contact element 115 and the stationary contact element 112.

Referring now to Figs. 20 and 21, in this modification a very simple mechanism is provided whereby to adjust the pressure between the creeping element 52 and the track 63. In this form of the invention the frame 42 has formed thereon a curved, notched bar 120. The creeping element 52 is carried by suitable arms 50 and 51, the arm 50 in this instance being provided with an offset portion 121 to which a pull chain 122 is attached. A spring plate 123 is fastened to the frame 42 and has ears like the ears in Figs. 1 to 3, inclusive, supporting a pivot pin 124 on which the arms 50 and 51 are secured. A spring 125 is mounted about the pin 124 and has one end bearing on the plate 123 and the other end fixed to the arm 50 so as to tend to move the creeping element into the position shown in Fig. 1.

In order to adjust the pressure of the creeping element upon the track I provide a wire 126, one end 127 of which extends through an aperture 128 in the corner of the frame 42 and the other end of which extends past the notched bar 120 so that it rides in the notches in the bar. This wire has an offset portion 129 behind the plate 123, the offset portion being adapted to move the free end of the plate 123 out away from the base of the frame 42 more or less depending upon which notch in the bar 120 the end portion 130 of the wire happens to engage. I find that this mechanism gives me an unusually wide range of adjustment for the pressure between the creeping element. Furthermore, it is particularly use-

ful for getting very fine adjustments and it is inexpensive to manufacture.

From the foregoing description it is believed that the construction and operation of the device embodying my invention will be clear to those skilled in this art. Having thus described my invention what I claim as new and desire to secure by Letters Patent is:

1. Time delay control mechanism of the character described comprising a movable member, means for urging said member in one direction, a relatively stationary member, one of said members having a yieldable creeping element and the other member having a track along which the creeping element must travel, the creeping element being compressed by engagement with said track whereby to oppose the force of said urging means, one of said members including a temperature responsive device for varying the pressure of the creeping element upon the track.

2. A time delay control mechanism of the character described, a spring pressed actuating member, and a relatively stationary member for retarding movement of said actuating member, said members having cooperating elements engaging each other yieldingly under pressure to oppose movement of said actuating member, and temperature responsive means to vary the pressure between said elements in response to temperature changes.

3. A time delay mechanism comprising a creeping element of resilient material, the hardness of which changes in response to changes in the temperature thereof, a track along which said element creeps, means urging said element along the track, supporting means for said element and the track and temperature responsive means forming part of said supporting means arranged to vary the spacing of the element and track to compensate for the change in hardness of the creeping element.

4. A time delay mechanism comprising a creeping element of resilient material, the hardness of which changes in response to changes in the temperature thereof, a track along which said element creeps, and a support for said track comprising a bimetallic strip operable to increase the spacing of the creeping element and track as the creeping element hardens.

5. Time delay control mechanism of the character described comprising a movable member, means for urging said member in one direction, a relatively stationary member, one of said members having a yieldable creeping element and the other member having a track along which the creeping element must travel, the creeping element being compressed by engagement with said track whereby to oppose the force of said urging means, and a temperature responsive device operably associated with said elements and urging means to oppose changes in the rate of creeping of the creeping element along the track element due to temperature changes of the elements.

6. Time delay control mechanism of the character described comprising a movable member, means for urging said member in one direction, a relatively stationary member, one of said members having a yieldable creeping element and the other member having a track along which the creeping element must travel, the creeping element being compressed by engagement with said track whereby to oppose the force of said urging means, and a temperature responsive device operably associated with said elements and urging

means to oppose changes in the rate of creeping of the creeping element along the track element due to temperature changes of the elements, said temperature responsive means comprising a bimetallic strip carrying one of said elements.

7. A time delay mechanism comprising a creeping element, a track element, one movable along the surface of the other in response to force applied thereto, said elements being positioned to press against each other during their creeping movement and temperature responsive means operably connected to said elements to oppose change in the rate of creeping of one element along the other due to changes in the temperature of the elements.

10 8. A time delay mechanism comprising a creeping element, a track element, one movable along the surface of the other in response to force applied thereto, said elements being positioned to press against each other during their creeping movement and temperature responsive means operably connected to said elements to oppose change in the rate of creeping of one element along the other due to changes in the temperature of the elements, said temperature responsive means comprising a bimetallic strip carrying one of said elements.

15 9. A time delay mechanism comprising a creeping element, a track element, one movable along the surface of the other in response to force applied thereto, said elements being positioned to press against each other during their creeping movement and temperature responsive means operably connected to said elements to oppose change in the rate of creeping of one element along the other due to changes in the temperature of the elements, said temperature responsive means comprising a bimetallic strip and said track element comprising a portion of said strip.

20 10. A time delay mechanism comprising a bimetallic strip, a portion of said strip being bent with respect to the remainder thereof to provide a track, a creeping element, a lever arm carrying said element, and yieldable means for moving said lever arm to force the creeping element along the track.

25 11. A time delay mechanism comprising a bimetallic strip, a portion of said strip being bent with respect to the remainder thereof to provide a track, a creeping element, a lever arm carrying said element, and yieldable means for moving said lever arm to force the creeping element along the track, said creeping element comprising a roughened metal core and a covering of rubber.

30 12. A time delay mechanism comprising a bimetallic strip, a portion of said strip being bent with respect to the remainder thereof to provide a track, a creeping element, a lever arm carrying said element, and yieldable means for moving said lever arm to force the creeping element along the track, said creeping element being movably mounted on the lever for limited movement in a direction diagonal to its path of movement across the track whereby when crossing the track in one direction the element may recede from the track but when crossing the track in the opposite direction the element may not recede from the track.

35 13. A time delay mechanism comprising a bimetallic strip, a portion of said strip being bent with respect to the remainder thereof to provide a track, a creeping element, a lever arm carrying said element, and yieldable means for moving said lever arm to force the creeping ele-

ment along the track, said lever arm being mounted for movement toward and away from the track, and means to adjust the lever toward and away from the track.

14. A time delay mechanism comprising a bimetallic strip, a portion of said strip being bent with respect to the remainder thereof to provide a track, a creeping element, a lever arm

carrying said element, and yieldable means for moving said lever arm to force the creeping element along the track, said lever being pivoted upon a base plate, and cam means for adjusting the base plate and lever toward and away from the track.
